Primary Examiner — Brett Miller*Assistant Examiner* — Jessica M Gebhart(74) *Attorney, Agent, or Firm* — QuickPatents; Kevin Prince(57) **CLAIM**

The ornamental design for a drone deployed water rescue bag, as shown and described.

DESCRIPTION

FIG. 1 is a perspective view of a drone deployed water rescue bag, showing my new design in an assembled configuration;

FIG. 2 is a top plan view of FIG. 1;

FIG. 3 is a bottom plan view of FIG. 1;

FIG. 4 is a bottom plan view thereof, illustrated in an open configuration;

FIG. 5 is a perspective view thereof, illustrating a bottom portion and a top portion detached from each other;

FIG. 6 is a top plan view thereof, illustrated in a separated configuration showing a bottom side of the top portion, and a top side of the bottom portion;

FIG. 7 is a front elevational view of FIG. 1;

FIG. 8 is a rear elevational view of FIG. 1;

FIG. 9 is a left-side elevational view of FIG. 1; and,

FIG. 10 is a right-side elevational view of FIG. 1.

The dashed, evenly spaced broken lines represent stitching and are included in the claimed design. The dotted broken lines show a logo and portions of the article that form no part of the claimed design.
